ULTRA HIGH FREQUENCY APPARATUS

Anatole M. Gurewitsch, Schenectady, N. Y., assignor to General Electric Company, a corporation of New York

Application November 20, 1944, Serial No. 564,383

3 Claims. (Cl. 178—44)

1

This invention relates to high frequency apparatus and is concerned primarily with the provision of new and improved means and methods for obtaining wide band modulation of cavity resonator circuits such as are employed in ultra high frequency amplifiers and oscillators.

When operating high frequency cavity resonator circuits as ultra high frequency amplifiers and oscillators and employing plate modulation to obtain wide band modulation of the resonators, it has been found that the capacity which ultra high frequency chokes or by-pass condensers normally introduce across the source of modulation makes most difficult and, in many cases practically impossible, the obtaining of wide band modulation. It is an object of the present invention, therefore, to provide an improved ultra high frequency choke for use in cavity resonators.

It is a further object of the present invention to provide a new and improved ultra high frequency choke which is tunable over a broad range.

It is a still further object of the present invention to provide a new and improved high impedance choke for a cavity resonator which has a minimum capacity to ground and which does not add to the interelectrode capacitance of an electronic tube used in the resonator.

An important feature of the present invention consists in the use of an ultra high frequency choke within a tubular anode of an electron discharge device used in a cavity resonator, the choke being placed essentially entirely within a region surrounded by the anode so that the component parts thereof having a minimum capacity to other elements of the resonator and, specifically, do not add to the anode-grid or anode-ground capacitance of the discharge device.

The features of the invention desired to be protected herein are pointed out in the appended claims. The invention itself, together with further objects and advantages thereof, may best be understood by reference to the following description taken in connection with the drawing in which Fig. 1 is a sectional view of an ultra high frequency oscillator-modulator employing cavity resonator circuits suitably embodying the invention, and Figs. 2-5 illustrate modifications of the ultra high frequency choke employed in the system of Fig. 1.

Referring particularly to Fig. 1, there is shown an oscillator of the re-entrant cavity resonator type, which has as its central element a high frequency electron discharge device such as the triode 1 comprising spaced planar electrodes including an anode 2, a control grid 3, and a cath-

2

ode 4. The anode 2 and cathode 4 preferably are cylindrical structures having their electron receiving and emitting surfaces, respectively, at the opposed ends of the axially aligned cylindrical structures. The grid or control electrode 3 is supported in spaced relation between the active surfaces of the anode and cathode by means of a metallic disk 5 which forms an external connection for the grid. Vitreous members 6, 7 are sealed between the anode and grid and the cathode and grid, respectively, to support the electrodes in spaced relation and form an enclosing envelope for the electron discharge path of the tube. The cathode 4 may be heated by the usual filament (not shown) supplied with heating current over a transmission line having an inner conductor 8 and an outer conductor 9, and the outer conductor 9 may serve as an external connection for the cathode. Direct current connections to the anode are made over a conductor 10 which likewise serves as means for supplying modulating potentials to the anode circuit.

The operating system in which the tube 1 is incorporated comprises a cavity resonator structure having as its principal component an elongated conductive member illustrated as cylinder 11 and formed, for example, of copper or brass preferably silver plated. This cylinder surrounds the tube 1 and is symmetrical with respect to the axis of alignment of the electrodes of the tube. A conductive wall part 12 extends across one end of the cylinder 11 and is provided with an inwardly directed portion 13 which engages the outer surface of the cathode 4, the resilient fingers 14 of the part 13 providing a mount for the tube 1. The cavity resonator defined by the cylindrical conductor 11 is of the concentric conductor type and the part 13 forms a portion of the inner conductor of this resonator. The remainder of the inner conductor comprises a conductive tube 15, provided with spring fingers 16 which engage the outer surface of anode 2, and an additional longitudinal conductive tube 17, the adjacent ends of the conductive tubes 15, 17 being spaced 45 apart by a small insulating gap 18.

The grid disk 5 is peripherally connected to a tubular conductor 19 and through that conductor with a terminal wire 20 which extends through an insulating bead 21 provided in a wall of cylinder 11 and is connected to one terminal of an external bias resistor 22, the other terminal of the resistor being connected to the outer surface of the member 11. The tubular conductor 19 is supported by a plurality of posts or insulators 23. The left-hand end of the tubular conductor

19 is spaced from the end wall 12 and the right-hand end of the conductor 19 is made adjustable in length by means of an additional tubular conductor 24 provided with spring fingers 25 for engaging the outer surface of conductor 19 and slidably along that outer surface, its position being adjusted by means of an external rod 26. The dimensions of the cavity resonator defined by the cylinder 11 and the inner conductor comprising members 13, 15, 17 may be adjusted by means of a plunger 27 having two sets of contact fingers 28, 29 which respectively bear upon the opposed surfaces of the parts 11, 17. The plunger may be moved back and forth by an externally accessible actuating rod 30 and, by this means, the size of the resonant cavity may be adjusted as desired.

Viewing the structure of Fig. 1 as a device for generating sustained oscillations, it may be noted that the triode 1 comprises means for exciting the system provided by the cylinder 11. When voltage variations are caused to occur between the grid and anode of the tube 1 at the resonant frequency of the cavity resonator 11, as modified by the presence of the tubular conductors 19, 24 and the tube 1, electromagnetic waves of the frequency in question will be established in the resonator defined by the inner and outer concentric conductors. Such waves may be considered as being initiated in the vicinity of the grid-anode gap and as being propagated from this point throughout the remainder of the resonator. Their path of propagation is governed by the presence of the conductive tubes 19, 24 which tend to confine or guide the waves along the annular space between these tubes and the conductors 15, 17. At the extremity of the tube 24, the waves are free to pass through the region bounded by the outer surfaces of the conductors 19, 24, the cylinder 11 and the plunger 27. Wave energy issuing from within the tubes 19, 24 can flow in the reverse direction along the outside of these conductors to the vicinity of the cathode-grid gap of the triode 1. When desired phase or magnitude relationships of the waves supplied from the grid-anode gap to the grid-cathode gap are established, regenerative oscillations are produced. The oscillator may also be operated as a plate modulator by supplying modulated potentials to the conductor 10 connected to the anode 2.

In order that high frequency energy may be taken from the cavity resonator for utilization in an external circuit, there is provided an output electrode which is illustrated, for example, as of the capacitive type which comprises a probe or disk 31 which extends into the resonator adjacent the outer surface of tubular conductor 19 and which is supported from a conductor 32 which forms the inner conductor of a concentric transmission line, the outer conductor 33 of the line being conductively connected to cylinder 11.

In order to prevent ultra high frequency energy within the cavity resonator from flowing through gap 18 and the undesired path established between the conductors 10 and 17, a choke is provided and comprises the cavity resonator defined by the inner surface of tubular conductor 15 and the outer surface of conductor 10 and tuned by means of a plunger 34. The plunger 34 bears two sets of contact fingers 35, 36 which respectively engage the opposed surfaces of the conductors 15, 10. The plunger 34 may be moved back and forth for tuning the cavity resonator by an externally accessible actuating rod 37. By adjustment of the position of plunger 34, the choke

is made resonant at a quarter wave length mode of the high frequency oscillations established within the principal cavity resonator. The result is that a high impedance is created in series with the concentric transmission line formed by conductor 10 and the inside of tubular conductor 17. Leakage of high frequency energy to the outside is made negligible as a consequence. One of the advantages of the high frequency choke thus formed is that the resultant capacity between ground and the source of modulation connected to conductor 10 consists only of the capacity across the gap 18 between adjacent ends of conductors 15, 17 in parallel with the capacities which exist between conductors 10 and 15 and the grounded cylinder 11. These latter capacities may be made reasonably small so that, as a result, all ultra high frequency currents are guided to the cavity resonator and all modulating frequencies and unidirectional currents are maintained in their proper channels and good modulation obtained.

An additional advantage of the ultra high frequency choke consists in the structure by which all metallic parts of the choke are placed inside the conductive tube 15, which functions as an extension of the anode 2, and, as a result, have no effect on the low frequency capacity of the anode, since the region within the tube 15 is essentially completely shielded for low frequency currents.

A modification of the ultra high frequency choke which is particularly useful when the oscillator operates at low frequencies is illustrated in Fig. 2, in which the physical size of the cavity resonator or choke in the extended anode member 38 is reduced by a tunable foreshortening capacity. The member 38 engages at one end the outer surface of anode 2 and at its other end is provided with a disk 39 attached to this inner surface. A disk or plate 40, slidably along the conductor 10 by means of actuating rod 37, forms with disk 39 a tuning capacitance which not only foreshortens the length of the cavity resonator but permits use of this type of choke over a wide frequency range. A particular advantage of this structure is that ultra high frequency voltage alone and no unidirectional voltage is developed across the capacity which exists between plates 39, 40.

In the modification of the ultra high frequency choke shown in Fig. 3, small physical size of the choke is achieved by folding the concentric transmission line resonator several times. This folding is obtained by using a pair of tubular conductors 41, 42 concentrically positioned within the extended anode conductor 43. The conductor 42 has an end wall 44. Preferably, in this form of the choke the member 42 is fixed upon the conductor 10 so that the choke operates at a fixed frequency determined by the effective electrical length of the sinuous concentric transmission line formed by the folded conductors 41-43. This frequency obviously is considerably lower than the frequency obtainable with the chokes illustrated in Figs. 1 and 2.

Fig. 4 illustrates an arrangement of wave chokes in series to cover a wide frequency band without requiring any adjustment or positioning of the members of individual chokes. In this form of the invention, the hollow extended anode cylinder 45 concentrically surrounds a plurality of cup-shaped conductors 46-48. The conductors 46-48 are of different lengths and the length of each of the conductors is selected to equal a quarter wave length at a desired frequency in

the frequency band to be covered by the ultra high frequency apparatus with which the choke is employed.

In the form of the invention shown in Fig. 5 there is illustrated an arrangement of a plurality of chokes which is electrically equivalent to that of the arrangement of Fig. 4 with the exception that the arrangement of Fig. 5 is physically more compact. In this modification, the conductive cylinders 49, 50, concentrically disposed about the conductor 10 and within the extended anode cylinder 51, are of different lengths and the concentric transmission line resonators defined by the inner and outer surfaces of respective pairs of these conductors act to suppress the flow of ultra high frequency energy between the conductors 10 and 17 at different points in the frequency band covered by the apparatus with which the choke is employed. In all of the structures shown in Figs. 1-5, the conductor 10 may be hollow and may serve to supply cooling fluid to the anode of the electron tube 1.

It is apparent that, by placing the metallic elements of the ultra high frequency choke essentially entirely within a region surrounded by an active conductor of the cavity resonator with which it is employed, minimum capacity between these elements and the remaining conductors of the ultra high frequency circuits is established. Specifically, in the forms illustrated, the choke, by being contained inside a conductive cylinder attached to the anode and operating at the same unidirectional potential, does not increase either the capacity between the anode and grid of the tube 1 or the capacity which exists between the anode and the grounded tubular conductor 11. Moreover, since the active elements of the choke are all maintained at the same unidirectional potential, the total unidirectional capacity of the resultant choke is kept at a minimum value with resultant improved operation of the high frequency apparatus either as a modulator or as an amplifier.

While the invention has been described by reference to particular embodiments thereof, it will be understood that numerous modifications may be made by those skilled in the art without departing from the invention. I, therefore, aim in the appended claims to cover all such equivalent variations as come within the true spirit and scope of the foregoing disclosure.

What I claim as new and desire to secure by Letters Patent of the United States is:

1. In combination, a high frequency resonator comprising a tubular outer conductor, a hollow inner conductor concentrically supported within said outer conductor, a section of said inner conductor being operated at a unidirectional potential difference with respect to said outer conductor and being separated from the remainder of said inner conductor by an insulating gap, a

lead-in conductor conductively connected to said section and concentrically supported within said inner conductor to form therewith a section of concentric transmission line, and means within said section of said inner conductor for tuning the section to prevent leakage of energy from said resonator through said gap.

2. Ultra high frequency apparatus comprising a tubular outer conductor and a centrally disposed tubular inner conductor, said conductors defining a high frequency resonator, means for exciting said resonator, said inner conductor including a portion operated at a unidirectional potential difference with respect to said outer conductor and the remainder of said inner conductor and being separated from said remainder by an insulating gap, a lead-in conductor to said portion concentrically supported within said inner conductor to form therewith a section of concentric transmission line, and means for preventing flow of high frequency energy from said resonator through said gap and said transmission line comprising an adjustable plunger within said portion for tuning said portion to the resonance frequency of said resonator.

3. Ultra high frequency apparatus comprising a tubular outer conductor and a centrally disposed tubular inner conductor, said conductors defining a high frequency resonator, means for exciting said resonator, said inner conductor including a portion operated at a unidirectional potential difference with respect to said outer conductor and the remainder of said inner conductor and being separated from said remainder by an insulating gap, a lead-in conductor to said portion concentrically supported within said inner conductor to form therewith a section of concentric transmission line, and means for preventing flow of high frequency energy from said resonator through said gap and said transmission line comprising a plunger conductively connected between the inner surface of said portion and said lead-in conductor for adjusting the length of the transmission line defined by said lead-in conductor and said portion to a value equal to a quarter wave length at the operating frequency of said resonator.
